AWNNG

William I. Smith, Perrysburg, Ohio, assignor to
The Hetrick Manufacturing Company, Toledo,
Ohio, a corporation of Ohio

Application August 16, 1944, Serial No. 549,641

2. Claims. (Cl. 160—57)

This invention relates to awnings and an object is to produce a new and improved awning, one or more walls of which are at least partially formed of foraminous material such as relatively close woven screening primarily to afford ventilation to the under portion of the awning.

Another object is to produce an awning, the walls of which are of canvas-like material except for screening material attached to the adjacent canvas portion by a sewed seam with the view of affording light and air to the under portion of the awning.

A further object is to produce an awning of the above character at least a portion of one wall of which is formed with foraminous material such as a plastic screen of sufficiently small mesh to repel rain but through which may pass light and air.

Embodiments of the invention are shown in the accompanying drawing by way of illustration and in such drawing:

Figure 1 is a front perspective view of an awning the side walls of which are provided with a strip of screen material;

Figure 2 is a fragmentary front perspective view in which the side walls are formed with a triangular insert of screen material;

Figure 3 is a fragmentary front perspective view in which the entire side walls except for the valance are formed of screen material;

Figure 4 is a side elevation of an awning showing the side wall thereof formed with a series of alternating vertical strips of screen and canvas-like material; and

Figure 5 is a fragmentary front perspective view of an awning, the sloping front wall of which is formed with a strip of screen material.

Referring to Figure 1 of the drawing, the awning comprises a sloping front wall 10 and generally triangular shaped side walls 11 which are connected to the sloping side edges of the front wall. Depending from the front wall 10 and each of the side walls 11 are valances 12. The top edge of the front wall 10 is formed with the usual horizontal pocket 13 containing the stiffening member (not shown) and grommets 14 are adapted to be slipped over connections 15 for supporting the awning in position of use. In this instance, the front wall 10 on the valances 12 are of textile fabric such as canvas or canvas-like material. The side wall 11 is formed of a triangular section 16 also of canvas-like material and the sloping upper edge of the section 16 which is spaced from and parallel with the side edge portion of the sloping front wall 10, has an

interposed section 17 of relatively fine mesh screening preferably of plastic strands of reasonable flexibility and suitably colored for the purpose. The screen cover 17 is attached to the canvas-like section 16 by a sewed seam 18 and to the edge portion of the sloping front wall 10 by a sewed seam 19.

It will be manifest that the screen 17 not only affords ventilation to the under side of the awning but also affords light thereto. The screen mesh should be sufficiently fine to act as a rain repellent so that except for a hard driving rain directly against the screen, water will not enter the under portion of the awning. It will be understood that the opposite side wall is similarly formed and detail description and illustration thereof is not considered necessary.

In Figure 2, the side wall 10a is similarly formed of canvas-like material and the section 16a of each side wall 11a is formed adjacent the upper portion with a screen section 17a which is attached to the adjacent portions of the wall section 16a and the sloping front wall 10a by sewed seams.

25 In the form shown in Figure 3, the sloping front wall 10b is likewise of canvas material and in this instance each side wall 11b is formed entirely of screen material similar to that above described. However, the valance 12b is of canvas-like material similar to that above described.

30 Referring to Figure 4, the top wall 10c is of canvas-like material and each side wall 11c is formed of alternating screen sections 17c and canvas-like sections 16c which are arranged vertically and thereby somewhat increase the screen area of the side walls. The vertical sections 16c and 17c are attached to each other by sewed seams and are in turn screened to the top wall 10c by a sewed seam. The valance 12c is of canvas-like material and may be secured in place by a sewed seam.

35 In the form shown in Figure 5, the sloping front wall 10d has a lower canvas-like section 20 to which the valance 12d is suitably attached. The upper portion or section 21 of the front wall 10d is formed by a horizontal strip of screen material attached to the section 20 by a sewed seam, and to a strip 22 at the upper edge which contains the attaching grommets 14d and the pocket 13d for the reenforcing or stiffening rod. In this instance, the side walls 11d are of canvas-like material and are suitably attached at their upper edge portions to the front wall 10d.

40 It will be observed that in each of the forms above described, foraminous or screen material

forms at least a portion of one of the walls thereby to afford light and ventilation to the under side of the awning. In this manner, an outstanding objection to the use of awnings is obviated since not only does the awning protect the associated window from the hot rays of the sun, but at the same time it enables additional light to enter and also to enable air to pass through and circulate under the awning, adding to the desired qualities of the awning. The screen material such, for example, as a plastic screen, lends itself readily to use in this connection and by employing sewn seams, the awning can be produced with existing machinery ordinarily used in the awning manufacture.

It is to be understood that changes of details of construction and choice of materials may be effected without departing from the spirit of the invention especially as defined in the appended claims.

What I claim is:

1. An awning structure having a slanting top

wall and side walls depending from the side edges of the slanting top wall, a light and ventilation opening in at least one of said walls, said opening being completely covered by fine mesh screen material adapted to act as a repellent of rain water, said screen material being flexible to permit the usual operation of the awning and being integrally united to the awning material by a sewn seam extending along the marginal edges of the screen.

- 5 2. An awning structure having a slanting top wall and side walls depending from the side edges of the slanting top wall, a light and ventilation opening in each of the said side walls, said openings being completely covered by fine mesh screen material adapted to act as a repellent of rain water, said screen material being flexible to permit the usual operation of the awning and being integrally united to the awning material by a 10 20 sewn seam extending along the marginal edges of the screen positioned in each opening.

WILLIAM I. SMITH.
